UNITED STATES PATENT OFFICE.

FAY H. WEBSTER, OF MARVELL, ARKANSAS.

SIGNAL SYSTEM.

1,109,381.

Specification of Letters Patent.

Patented Sept. 1, 1914.

Application filed January 17, 1913. Serial No. 742,599.

To all whom it may concern:

Be it known that I, FAY H. WEBSTER, a citizen of the United States, and a resident of Marvell, in the county of Phillips and State of Arkansas, have invented a new and Improved Signal System, of which the following is a full, clear, and exact description.

This invention relates generally to a visual signal, and is more particularly directed to an electrically-actuated mechanism adapted for coöperation with a telephone circuit.

The purpose of the invention is to provide a visual signal in connection with a telephone circuit, whereby the central office may throw into exposed position a semaphore arm, or may light a lamp located at any suitable point, the signal-actuating mechanism being controlled by the calling current through the telephone.

The signal is primarily intended for use in public places, as in connection with police service, allowing headquarters to set a visual signal at any police booth, thus notifying officers on beat to call up headquarters for instructions.

The construction illustrated and described makes use of a semaphore arm and a lamp as signal elements; the construction described contemplates a means for preventing constant burning of the lamp when the semaphore arm is exposed, as during the day time when such lamp is not needed.

Many objects and advantages following the use of the invention will appear as the description proceeds, the inventive idea being comprehended in the scope of the appended claims.

Reference is to be had to the accompanying drawings forming a part of this specification, in which like characters of reference indicate corresponding parts in all the views, and in which—

Figure 1 discloses diagrammatically the arrangement of the signal on a pole; Fig. 2 is a similar view showing the semaphore in exposed position; Fig. 3 is a similar view disclosing the relative positions of the parts when the semaphore is returning to unexposed position. Fig. 4 is a fragmentary view illustrating a slightly modified form.

The invention is described in connection with a pole 1, having a telephone 2 thereon, usually contained within a housing 3, the wires 4 serving to connect the telephone with the central office; these parts are chosen

merely in order to show the utility of the invention, it being obvious that many different arrangements may be used.

Pivotedly mounted on the pole in any suitable manner, as by means of a pin 5, is a semaphore arm 6, having a short arm 7 at one end to which is connected a rope or chain 8, terminating in a ring 9 extending adjacent the telephone 2, the said ring and chain serving as a means of returning the semaphore arm from the position shown in Fig. 2 to that shown in Fig. 1. Extending laterally from one side of the semaphore arm 6 are a hooked arm 10 and an offset 10'.

Adjacent the semaphore, and carried on the pole 1, is a lamp 11, one of the wires 12 thereto communicating with one side of a battery 13, or other source of electrical energy; the other wire 14 extending from the lamp is connected to one end of the electro-magnet 15, the other wire 16 from the electro-magnet extending downwardly, and preferably into the housing 3 which carries the telephone; the wire 17 extending from the other side of the battery 13 also extends into the housing 3.

Adjacent the electro-magnet 15 is an armature 18, pivotally mounted in position at 19, the armature being in electrical contact with the wire 17 through a conductor 20; the outer end of the armature is hooked, as at 21, and in the normal position of the parts as shown in Fig. 1 the engagement of the hooked end of the armature with the hooked end 10 of the semaphore arm serves to retain the parts in the position shown. Carried on the pole 1 is a resilient element 22 having a contacting finger 23 adapted to be engaged by a contact 24 on the armature 18 when the same comes into the position shown in Fig. 2; this finger 23 is connected with the wire 16 leading from the electro-magnet 15 by means of a conductor 25. As noted particularly in Figs. 1 and 2, a buffer 26 of any suitable form, preferably a resilient arm, is carried by the pole 1 and serves to take up the shock of the falling semaphore arm.

Within the housing 3 is a relay made up of the electro-magnet 27, the pivoted armature 28, the fixed contact 29, the stop 30, and the spring 31. The wire 17 leading from one side of the battery 13 is connected to the fixed contact 29, while the wire 16 leading from one end of the electro-magnet 15 is connected to the armature 28; the stop

30 determines the normal position of the armature relatively to the electro-magnet, the position being maintained by means of the spring 31, the stop 30 being adjustable 5 in order to limit the movement of the armature. The terminals of the electro-magnet 27 are connected to the wires 4 of the telephone by conductors 32. The electro-magnet 27 may be short-circuited, and the apparatus thereby rendered inoperative by means 10 of the switch 33 in multiple with the electro-magnet.

If the central station should call the telephone represented as 2, the calling current 15 would circulate through the electro-magnet 27 (if the switch 33 is open), the armature 28 being thereby drawn to the pole face of the electro-magnet and the circuit through the wires 16 and 17 being closed; the battery 20 13, or other source of electrical energy, will then energize the electro-magnet 15 adjacent the semaphore arm, drawing the armature 18 out of engagement with the hooked arm 10 of the semaphore, and permitting the said 25 arm to drop into the full line position of Fig. 2. The movement of the armature 18 as described will bring the contact 24 thereon into engagement with the finger 23, thereby placing the electro-magnet 15, the 30 battery 13 and the lamp 11 in circuit, the lamp remaining lighted. The electro-magnet 27 is actuated only during the time that calling current flows through the telephone 2.

35 Referring now to Fig. 3, the downward movement of the chain or rope 8 will bring the semaphore arm upwardly into the position shown in that figure, the curved offset 10' on the semaphore engaging the top corner 40 of the armature 18, thereby bringing the contact 24 thereon out of engagement with the contact finger 23, opening the circuit through the electro-magnet and the lamp, the lamp being thereby extinguished. Further downward movement of the chain or rope 8 will 45 bring the hooked arm 10 on the semaphore into engagement with the hooked end 21 of the armature 18, the parts being then in normal position, as shown in Fig. 1. If so desired, the lamp 11 may be rendered inoperative 50 by means of the switch 34 in multiple with the lamp, the closed position of the switch short-circuiting the lamp; this switch may be used through the day in order to 55 prevent the lamp burning, such switch, however, not preventing the continuous flow of current from the battery 13 through the electro-magnet 15, a modified construction being availed of to prevent this continuous flow 60 of current when so desired.

65 Referring particularly to the modified form shown in Fig. 4, it will be noted that extending outwardly from the end of the hooked arm 10 is an offset 35, which offset 70 engages the resilient finger or support 22

or the contact finger 23 as the semaphore swings outwardly to exposed position, bringing this finger out of engagement with the contact 24 on the armature 18, thereby opening the circuit through the lamp, battery 70 and electro-magnet, and preventing the continual burning of the lamp or continuous flow of current which would otherwise happen until the semaphore arm is returned to normal position. When the offset 35 is used 75 and when the arm 6 is in signal position, a second flow of current through the relay will of course operate the electro-magnet 15 and light the lamp. The use of the offset 35 is optional.

80 The structure set forth is simple, and while making use of elements which are now in use, the relation of the elements among themselves is such that a visual signal, particularly useful in connection with a telephone system, is provided, and one which is inexpensive in make-up and maintenance.

85 Having thus described my invention, what I claim as new and desire to secure by Letters Patent is:—

1. In a signal system, a relay including a visual signal, a source of current, and an electro-magnet, connected in series, a semaphore arm engaged and held in inoperative position by the armature of the electro-magnet, and contacts for bridging the relay circuit, one of which contacts is carried and movable with the armature of the electro-magnet to engage the other contact and 90 form a continuous circuit through the signal, source of current and electro-magnet when the relay circuit is completed to release the semaphore arm.

100 2. In a signal system, a relay circuit including a visual signal, a source of current and an electro-magnet connected in series, and the latter of which is energized when the relay is completed, a semaphore arm engaged and held in inoperative position by the armature of the electro-magnet, said armature being connected to one side of the relay circuit and provided with a contact member, and a contact member connected to the opposite side of the relay circuit, and 105 with which the armature carried contact engages when the armature is moved toward the electro-magnet to release the semaphore arm, and the electro-magnet is energized 110 by completion of the relay circuit.

115 3. A visual signal comprising a circuit 120 made up of a relay actuated device for closing the circuit, a source of current, a lamp and an electro-magnet, the said elements being connected in series, the armature of the electro-magnet being connected to one side 125 of the said circuit, a contact finger with which the armature is adapted to engage and connected to the other side of the circuit, a semaphore arm engaged by the said armature and maintained in one position, 130

movement of the armature when the electro-magnet is energized permitting the semaphore arm to come to a second position, the armature engaging the said contact finger, whereby a circuit is closed through the source of current, the lamp and the electro-magnet, the semaphore arm being provided with means for moving the said contact finger away from the armature when the semaphore falls, thereby opening the circuit through the said electro-magnet, lamp and source of current.

4. A signal system comprising a circuit made up of a circuit closing device, a source of current, a lamp and an electro-magnet, a semaphore arm, the armature of the electro-magnet engaging the semaphore arm and maintaining it in one position, closing of the circuit through the electro-magnet disengaging the armature from the arm and permitting the arm to come to a second position, the said armature being connected to one side of the circuit between the source of

current and the circuit closing device, a contact finger with which the armature is adapted to engage and connect to the other side of the circuit between the electro-magnet and the said circuit closing device, movement of the armature when the electro-magnet is energized bringing the armature into engagement with the contact finger, whereby a circuit is closed through the electro-magnet, source of current and the lamp, manual means for returning the semaphore to first position, and means on the semaphore engaging the armature and bringing it away from the said contact finger, whereby the circuit through the said lamp is broken.

In testimony whereof I have signed my name to this specification in the presence of two subscribing witnesses.
